UNITED STATES PATENT OFFICE.

GUSTAV J. FRIEDRICH, OF NEW YORK, N. Y., ASSIGNOR OF TWO-THIRDS TO HIMSELF AND ONE-THIRD TO ALFRED BAKER, TRUSTEES, OF NEW YORK, N. Y.

LOOM-SHUTTLE.

1,296,645.

Specification of Letters Patent. Patented Mar. 11, 1919.

Application filed May 1, 1916. Serial No. 94,581.

To all whom it may concern:

Be it known that I, GUSTAV J. FRIEDRICH, a citizen of the United States, residing at the borough of Manhattan, in the city, county, and State of New York, have invented certain new and useful Improvements in Loom-Shuttles, of which the following is a specification, reference being had therein to the accompanying drawings, 10 which form a part thereof.

My invention relates to loom shuttles and more particularly to a type of quick threading shuttles.

At the present time there is in extensive use loom shuttles having an eye in the side wall thereof adjacent one of the bearings for the cop, it being a common practice in using this type of shuttle for the operator to hold the end thereof on one side of the eye and to suck the thread through the eye. By means of a shuttle made in accordance with my invention, the operator is enabled to thread the shuttle more quickly than it is possible to thread the type of shuttle above 25 referred to, by merely applying pressure through a short section of the yarn held taut upon a threading device carried by the side wall of the shuttle adjacent the eye. By the use of a shuttle made in accordance 30 with my invention there is not only a saving of time in threading, but the unhygienic practices now commonly followed are avoided and injury to the health of the operator by reason of the inhaling of small 35 fibers from the yarn is prevented.

The shuttle is so constructed that the threading mechanism is substantially flush with the outside of the shuttle and the parts thereof are so arranged as to avoid any 40 tendency of such a disarrangement of parts as would interfere with the continued use of the shuttle.

The invention consists primarily in a shuttle having a recess in one side thereof, said 45 recess having a portion of a shuttle eye in one vertical wall thereof, a member movably mounted in said recess adapted to guide the yarn from the top of said recess into said eye-opening and a spring acting upon 50 said member whereby said member may be moved to permit the yarn to enter said eye opening and will be restored to normal after each threading operation; and in such other novel features of construction and combination of parts as are hereinafter set forth and

described and more particularly pointed out in the claims hereto appended.

Referring to the drawings:

Figure 1 is a plan view of a portion of a shuttle embodying my invention; 60

Fig. 2 is a perspective view of the mechanism mounted in the side wall of the shuttle for forming the eye and permitting the quick threading thereof, the parts thereof being shown separately; 65

Fig. 3 is a side elevation thereof;

Fig. 4 is a longitudinal section of a modified form of the invention; and

Fig. 5 is a side elevation of the form of the invention shown in Fig. 4. 70

Like letters refer to like parts throughout the several views.

In the embodiment of my invention shown in the drawings, *a* indicates one end of an ordinary flying shuttle. This shuttle has 75 mounted in one side wall thereof adjacent one end *b* of the cop *c*, a block *d* forming a part of said side wall and having therein a recess *e*. Extending transversely through the block *d* is a semi-circular opening *f* forming a portion of the eye of the shuttle. Movably mounted in the recess *e* is a block *g* 80 adapted to have limited reciprocatory movement toward and from the wall of the recess having the eye opening *f* therein, suitable guides being provided to define the movement of the said block and prevent its displacement while the shuttle is in use. 85

I also provide fillets and grooves *h*—*h'* for preventing displacement of the member 90 *g*. The member *g* has in that face thereof presented toward the wall of the recess having the eye opening *f* therein, an opening *d'* adapted to register with said first named opening *f* and form a round eye-opening. 95

Acting upon the member *g* is a spring *i* seated in a socket therein and acting against the wall of the recess *e* parallel with that wall of said recess having the eye opening *f* therein, this spring being so tensioned as to 100 normally force said member into the proper relation to the wall of the recess having the eye opening *f* therein, to form a continuous circular eye opening in the manner above referred to. 105

The adjoining top edges of the block *d* and member *g* are rounded off as shown at *j*—*j'* so that stresses from the thread section will move the member *g* against the tension of its spring in a manner to cause 110

said member and the adjoining face of the block d to guide the yarn to the eye-opening, said member automatically returning to normal as the yarn enters the eye.

5 In the form of the invention shown in Figs. 4 and 5, instead of employing a reciprocatory member such as g mounted in an angular opening in the block d , I provide a block d' having a circular opening extending therethrough, said opening having at the periphery thereof a portion k of the eye-opening. Inclosing the opposite sides of said circular openings are two disks $m-m'$ secured in the desired relation to each other 10 by means of a hub n . Mounted upon the hub n is a helical spring o acting upon the side wall of the block d' in a manner to normally turn the said disks to the right, (Fig. 5.) The circular opening through the block 15 d' is open slightly at the top so as to expose the tops of the disks $m-m'$, the exposed portions of said disks having a notch p therein adapted to receive the thread. Hence, a downward pressure will cause the said disks 20 to rotate against the tension of the spring o and deposit said thread in the eye-opening k . As the notch p comes to position opposite said eye-opening, the thread will leave the notch, thus permitting the spring to 25 release the disks to their normal position. The said disks are each provided with a semi-circular opening as q adapted to register with the opening k to form a circular eye-opening in the same manner as heretofore 30 described in connection with the form of the invention shown in Figs. 1 to 3.

In both forms of the invention shown, the threading attachment may be made of any desired material and since with the ordinary 35 shuttle, the only alteration necessary to permit the adaptation of this threading fitting thereto, is the cutting of a small section from the wall thereof, the fitting may be attached to shuttles now in use without material expense.

In threading shuttles made in accordance with my invention, the operator merely takes a short section of the yarn adjacent the end thereof and stretches it sufficiently 40 taut so that by exerting a downward pressure against the beveled edges $j-j'$ of the form of the invention shown in Figs. 1 to 3 this pressure will cause the member g to recede sufficiently from the wall of the block d having the eye opening therein to permit the yarn to slide between the side 45 wall of the block and the face of the movable member. As the yarn enters the eye-opening, the member g will return to its former position the end of the thread being presented outwardly of the shuttle.

While I have shown the eye opening in the block d as being a half circle it is apparent that if it be found desirable to make this 50 opening larger or smaller, this change may

be made without departing from the spirit and scope of the invention, since it is merely necessary that the portion of the eye extending through the recess to be opened sufficiently to permit the yarn to enter same. 70

In the form of the invention shown in Figs. 4 and 5, the operator will apply the taut section of yarn to the notch in the disks $m-m'$ with sufficient pressure to cause the turning of these disks so that the yarn 75 will be carried and guided between the disks and the adjacent wall of the block d , until the eye opening k is reached. Whereupon, the yarn will pass into said eye opening and the spring e will restore the disks to normal 80 in a manner to bring the portion of the eye-opening q therein to register with the eye-opening in the block d to form a circular eye opening as in the other form of the invention. In both forms of the invention, 85 the threading of the shuttle may be accomplished substantially instantaneously and the operator is not required to place his or her mouth about the eye opening while threading.

90 It is not my intention to limit the invention to the precise details of construction shown in the accompanying drawings, it being apparent that such may be varied without departing from the spirit and scope of the invention.

Having described the invention what I claim as new and desire to have protected by Letters Patent is:—

1. In a shuttle having a recess in a side wall 100 thereof, said recess having a portion of an eye opening in one of its vertical walls providing an opening through said wall, a threading means embodying therein a member movably mounted in said recess and 105 adapted to guide the yarn from the top of said recess to said eye opening, and a spring acting upon said member, whereby said member may be moved to permit the yarn to enter said eye opening, and will be restored to normal after each threading operation.

2. In a shuttle having a recess in a side wall thereof, said recess having a portion of an eye opening in one vertical wall thereof 115 providing an opening through said wall, a threading means comprising a movable member slidably mounted in said recess, said member having a complementary portion of said eye opening in that wall thereof presented toward the wall of said recess having said portion of an eye opening therein, and a spring acting upon said movable member, normally tending to force it toward said wall of said recess having said portion of an 120 eye opening, the edges of said recess and of said movable member above said eye opening, being rounded, whereby pressure from a taut section of yarn will actuate said movable member to permit the passage of said 125 130

yarn between said member and the wall of said recess, until it enters said eye opening.

3. In a shuttle having a recess in a side wall thereof, said recess having a portion of 5 an eye opening in one vertical wall thereof providing an opening through said wall, a threading means comprising a movable member slidably mounted in said recess, said member having a complementary portion of 10 said eye opening in that wall thereof presented toward the wall of said recess having said portion of an eye opening therein, means permitting reciprocatory movement of said member and preventing its escape 15 from said recess, and a spring acting upon said movable member, normally tending to force it toward said wall of said recess having said portion of an eye opening, the edges of said recess and of said movable member above said eye opening, being 20 rounded, whereby pressure from a taut section of yarn will actuate said movable member to permit the passage of said yarn between said member and the wall of said recess, until it enters said eye opening.

4. In a shuttle having a recess in a side wall thereof, said recess having a semi-circular eye opening in one vertical wall thereof of providing an opening through said wall, 30 a spring controlled, movable member nor-

mally closing said eye opening and adapted to have movement toward and from same, whereby when pressure is applied to said member by a taut section of the yarn, the yarn will be guided into said eye, and when 35 said yarn enters said opening, said member will return to normal.

5. A shuttle having seated on one side wall thereof a block having a recess therein, said recess having a portion of an eye opening in a vertical wall thereof, a member movably mounted in said block in said recess, said member being adapted to guide the yarn through said recess and said eye opening, a spring acting upon said member whereby said member may be moved to permit the yarn to enter said eye opening and to be restored to normal after each threading operation and co-operating means carried by said block and the wall of the shuttle whereby displacement of said block is prevented.

In witness whereof, I have hereunto affixed my signature in the presence of two subscribing witnesses, this 21st day of April, 1916.

GUSTAV J. FRIEDRICH.
